UNITED STATES PATENT OFFICE.

OTTO HIGEL, OF NEW YORK, N. Y.

PIANO-ACTION BRACKET.

1,406,382.

Specification of Letters Patent. Patented Feb. 14, 1922.

Application filed August 30, 1920. Serial No. 406,879.

To all whom it may concern:

Be it known that I, OTTO HIGEL, a British subject, and resident of the city and State of New York, in the United States of America, have invented certain new and useful Improvements in Piano-Action Brackets, described in the following specification and illustrated in the accompanying drawings, that form part of the same.

10 The principal objects of this invention are to devise a form of action bracket of a light and strong construction which may be readily manufactured in various lengths and will be cheap to produce.

15 Up to the present time it has been the practice to use a cast iron bracket for supporting piano actions and owing to the variations in dimensions and designs of pianos to which the action is applied, it is necessary 20 for the manufacturer to carry a large stock of different sizes and forms.

The present form of bracket enables the manufacturer to adjust the bracket to various dimensions owing to its being constructed 25 of sheet metal.

In the drawings, Figure 1 is a side elevation and part sectional view of my improved bracket showing the location of the various rails of the action.

30 Figure 2 is a perspective view of the bracket.

Figure 3 is a perspective view of a modified form of bracket.

The bracket consists of a sheet metal member 1 preferably formed of a U-shape or 35 channel cross section. The upper end is formed with a fork 2 which straddles the bracket bolt 3. An outward curve 4 is formed in the member 1 below the fork and 40 leads to a perpendicular portion 5 to which the spring rail 6 is secured.

An angular bracket member 7 has one end secured to the portion 5 of the back of the member 1 by a screw or rivet 8. The upper 45 portion 9 of this bracket forms the rest for the hammer rail 10. The outer portion curves downwardly and is securely riveted to a sloping portion 11 of the bracket 1.

The bracket 7 forms a finger grip for the 50 handling of the action. The inner end is formed with a loop 12 to which the swing arm 13 of the hammer rail 10 is pivotally secured.

Below the bracket 7 and at the opposite 55 side of the member 1 the edges of the chan-

nel-shaped member are formed with a plurality of serrated teeth 14 projecting beyond the edge of same and forming a contact surface for the main action rail 15, which is secured in an adjusted position by 60 the bolts 16 which extend through the back of the channel. The bottom or abstract rail 17 is supported from the lower vertical portion of the member 1.

At the bottom end the channel-shaped 65 member is flared outwardly and the web of the channel extends inwardly between the side flanges and is formed with a conical socket 18 adapted to rest upon the tapered end of the supporting bolt 19 which is 70 mounted in the key-board frame of the piano.

A rectangular slot 20 is cut through the lower end of the web of the channel and is adapted to receive the curved foot member 75 21. This curved foot member is formed with the notches 22 centrally of its length at the top and bottom and a flat strip of metal 23 of the same width as the said notches is bent around the member 21, fitting snugly into 80 the notches and this metal strip with the foot 21 fits snugly between the flanges of the channel-shaped bracket. The upper and meeting ends of the strip 23 are bent into a semi-cylindrical curved form which meet 85 and encircle the fastening rivet 24 which is secured in the web of the channel section. The foot is thus very securely held in a very simple and effective manner.

The various members of the action are 90 secured by means of suitable bolts or screws extending through the web of the bracket and they are adjustable on said bracket. If the adjustments required are abnormal, the bracket may be produced of substantially 95 the same pattern with the straight portion 5 of a greater length.

In the form of bracket shown in Figure 3, the design is of a straight form. The hammer rail bracket is substantially the 100 same as that shown in Figures 1 and 2 but the main rail support differs slightly. The support is formed of an L-shaped block 25, the bottom end 26 of which forms a foot projecting from the channel while the up- 105 right portion fits between the flanges of the channel. A sheet metal strip 27 is pressed into channel formation to fit around the member 25 within the channel of the bracket. This is wedged tightly into place 110

or may be fastened with a suitable screw if desired or it may be riveted or brazed in position.

The foot 28 is of an arc-shaped piece of sheet metal having a radial arm 29 which fits between the side packing plates 30 and is rigidly secured between the flanges of the main channel. The web of the channel is bent under the end and formed with a socket 31 similar to the socket 18.

Two different forms of sheet metal action brackets are herein shown and described but it must be understood that the actual design or shape of the bracket may be varied considerably and that any desired form of sheet metal may be used without departing from the spirit of the invention.

A bracket such as described may be readily bent to fit into pianos where only a slight variation occurs and it is also capable of being bent laterally so that it will be readily understood that a very great range of adjustment is possible where with cast metal brackets adjustment is impossible.

25 What I claim as my invention is:—

1. A piano action bracket, comprising, a channel shaped sheet metal arm having the web thereof bent inwardly at the end and

formed with a socket to rest upon the supporting bolt, and a top end adapted to engage the bracket bolt.

2. A piano action bracket, comprising, a sheet metal member in the form of an arm having a U-shaped or channel section bent to shape to engage and support the various action rails, a bracket connected to the web of the aforesaid bracket on the front side adapted to support the hammer rail, and a foot secured to the bottom of said bracket to support the bracket in a standing position.

3. A piano action bracket, comprising, a channel-shaped sheet metal member having serrations formed on the edges of the flanges intermediate of the length to engage and support the main action rail.

4. A piano action bracket, comprising, a bracket of channel-shaped section having a slot cut through the web adjacent to the bottom, a curved sheet metal foot extending through said slot and being notched in the top and bottom, a metal strip bent around said foot and resting in said notches and fitting snugly between the flanges of the main bracket securing the foot therein.

OTTO HIGEL.
